AUTOMATIC BAND CONTROL AND SIGNAL
FOR OVENSHarvey O. Mercier, East Orange, N. J., assignor to
National Biscuit Company, New York, N. Y., a
corporation of New Jersey

Application November 16, 1939, Serial No. 304,757

9 Claims. (Cl. 74—241)

My invention relates to an automatic band control and signal for ovens and is particularly adapted for use with ovens of the continuous band or conveyor types, although equally useful with many kinds of endless belts, conveyors, dryers or similar driven devices.

In recent years, ovens of the type having an endless band or other form of continuous carrier passing over drums at opposite ends of the oven, have come into extensive use. These ovens have been increased in size and capacity until the drums often are 250 to 300 feet apart and the bands twice that length. The steel band commonly used is enclosed within a heavily insulated housing or casing and practical construction requires that there be very little clearance allowed between the housing and edges of the band. This means that the band must be kept accurately centered on the drums and not permitted to run or shift to either side. If the band shifts very far it will strike the oven frame and cause great damage to one or the other because the bands cost thousands of dollars and also the oven frame is very expensive. Extensive injury to either is very costly. Even though the drums at the two ends of the oven are exactly cylindrical and exactly parallel and the band of exactly the same length throughout its width, the band will not always run true on the drums but shifts from side to side. This is because different parts of the band, which may be 500 to 600 feet long, expand unequally due to varying temperature and operating conditions within the oven and for other reasons that cannot be eliminated or always controlled. Heretofore, attempts have been made to keep the band running true on the drums by purely mechanical means, some of which are successful, but which cause considerable wear on the edges of the band because of the great pressure or force that they must exert to keep the band in its central or normal position on the drums, or return it if it is displaced.

The principal object, therefore, of the present invention is to provide means that will automatically keep the band running true on the drums within allowable limits without any injury or appreciable wear along its edges.

Another object is to provide means that will automatically return the band to central position on the drums, in case it does run to one side, and at the same time operate a visible or audible signal that will tell the operator that the band is off center.

Another object is to provide means that will automatically change the alignment of the drums

so as to cause the band to return to central position, if it has shifted to one side.

Still another object is to provide means that will automatically come into operation to shift 5 one of the drums relative to the other by one or more impulses, at spaced time intervals, until proper correction has been made.

Another object is to provide means that will automatically change the alignment of the drums 10 by a slight increment and then pause until the effect of the correction can be attained, usually by allowing for band travel from one drum to the other, then if sufficient correction has not been made, to continue making it at spaced intervals 15 until the band again runs centrally on the drums.

Another object is to provide an electrically operated means that will be controlled by the position of the oven band itself to keep the band running true on the drums.

Another object is to provide means in the electric control circuit that will automatically prevent over-correction or shifting of the drums too far out of parallel.

Another object is to provide in a band control 25 device a system of electric control circuits that will be controlled by the position of the band itself to operate a mechanical means intermittently to return the band to central position and also operate an audible or visible signal or signals at the same time.

The above and other objects and advantages are attained by my invention, one embodiment of which I have illustrated in the accompanying drawings wherein:

Fig. 1 is a diagram of the electric control circuits when inoperative or with the band running in central position.

Fig. 2 is the same diagram with the circuits closed as when the band has shifted far enough to close one of the control switches.

Figs. 3 and 4 are plan and side elevations, respectively, each partly in section, showing the electrically operated mechanical means for shifting one of the bearings of one of the drums to change their alignment when the band is off center.

Fig. 5 is a detail showing how the bearings may be adjusted manually.

Fig. 6 is a section through an oven showing somewhat diagrammatically how the control switches may be actuated by the oven band when the band runs to either side of its normal or central position.

I will first describe the mechanical parts of the control as exemplified in Figs. 3 to 6 and then the

electric circuits and controls of Figs. 1 and 2 which control the operation of the mechanical parts.

Referring first to Figs. 3 and 4, 1 and 2 are parts of the side frame members of the oven at one end on which are mounted the bearings 3 and 3' in which the shaft 4 that supports the drum 5 is rotatably mounted. The bearings 3, 3' may be self-aligning bearings of well known construction as indicated by dotted lines in Fig. 3 or that may fit the shaft 4 with sufficient play to enable the bearing 3 to be shifted slightly without binding on the shaft. There are two of these drums 5 over which the oven band passes, one at each end of the oven. One of the bearings, as 3, at either or both ends of the oven, is slidably mounted on the frame member 1. As shown in the drawings, the flanges of the bearing have slotted openings 6 engaged by bolts 7 which permit the bearing to have a sliding movement on the frame member. Any suitable mechanical means, such as a dovetail construction, may be used for slidably mounting the bearing. To shift the bearing back and forth I provide a screw threaded shaft or spindle 8 which engages in a screw threaded opening in a block 9 that is fixed to the oven frame adjacent the bearing 3. One end of this shaft has a collar and is rotatably secured in a split block 10 that is secured to the bearing 3. When this shaft 8 is rotating in either direction it will travel through the fixed block 9 and correspondingly shift the bearing 3 and change the position of the drum shaft 4 with respect to the drum shaft at the opposite end of the machine. Normally the two drum shafts at the two ends of the machine are parallel so that the continuous band runs uniformly over the two drums.

The shaft 8 is rotated by a reversible electric motor 11, which preferably is a three phase motor, but may be any suitable kind, and is connected through a reduction gear to drive a grooved pulley or sprocket 12 that rotates on a shaft 13 journaled in a casting 14 that is secured to the oven frame member 1. The shaft 13 carries a worm 15 which meshes with a worm wheel 16 that is pinned to the shaft 8 so that the shaft can slide with respect to the worm wheel. A hand wheel 22 is splined to the shaft 13 so that it can slide with respect thereto and has clutch elements 23 adapted to engage corresponding elements in the sprocket 12 so as to key the sprocket to the shaft 13. When it is desired to adjust the bearing 3 by hand, the clutch elements 23 are disengaged from sprocket 12 as shown in Fig. 5 and the shaft 13 rotated by hand until the desired adjustment is attained. In normal operation the clutch 23 engages in the sprocket 12.

The free end of the shaft 8 is connected to a swinging arm 17 that may be pivoted at its lower end to the oven frame and at its free end carries a pair of adjustable stops 18, 19 that are adapted to strike the abutments or knobs 20, 21 of a pair of limit switches R4 and L4 in the control circuit of the motor 11 and which normally are closed. The amount that the bearing 3 is shifted in any case is very slight and the limit switches and stops 19, 20 are provided as a safety means so that the motor circuit will be opened and the motor stopped before the bearing 3 can be shifted far enough, or the shaft 4 thrown far enough out of alignment to cause any damage.

The motor 11 is operated intermittently, when the oven band has shifted to one side or the other, to shift the bearing 3 by a series of nudges or impulses until the position of the band has been

corrected. The action of the motor 11 is controlled by a pair of timing switches, one of which determines the length of the intervals between impulses, and the other determines the length of the impulse itself. The intervals between impulses are timed so that the band can make one complete travel through the oven before a second impulse is imparted to the motor and bearing 3. The interval between impulses will be adjusted according to the baking interval of the oven at that particular time and usually will run from three to eight minutes. The impulse itself is very short and the motor will operate only long enough to rotate the shaft 13 about two revolutions which will shift the bearing 3 about .014 of an inch in the form of the invention shown. The time interval of the impulse will usually be only from two to four seconds. In case the impulses continue in one direction so long that there is danger of shifting the bearing 3 too far, then either stop 18 or 19 will strike abutment 20 or 21 and open the switch R4 or L4, as the case may be, and stop the motor but the signals will continue to operate. When this occurs it indicates that there is something seriously wrong and no further adjustment can be made until the trouble has been corrected.

The operation of the motor 11 is controlled by the shifting of the band within the oven. Referring to Fig. 6, a section of the band is indicated at 24 and this band travels adjacent a pair of control switches R and L which have rollers 25, 26 adjacent the edges of the band and adapted to be engaged by the band when it shifts to either side. The rollers 25, 26 are carried by levers 27, 28 pivotally mounted on brackets 29, 30 secured to the oven frame adjacent the edges of the band. The lower ends of the levers 27, 28 are connected to a pair of slides 31, 32 adapted to engage the operating levers 33, 34 of the control switches R and L. I have shown the switch R on the right-hand side of Fig. 6 and the switch L on the left-hand side. Switch R is connected in an electric circuit to control the operation of the motor 11 when the band shifts to the right and the switch L is connected in the circuit to control the operation of the motor 11 when the band shifts to the left. The motor is driven in one direction when the switch R is closed and in the opposite direction when the switch L is closed.

The electric circuits for controlling the intermittent operation of the motor 11 and also for operating a set of visible and audible signals are shown diagrammatically in Figs. 1 and 2.

Fig. 1 shows the circuits when the band 24 is in its normal or central position.

Fig. 2 shows the circuits when the band 24 has shifted to the right so as to close the control switch R.

The operation of the automatic control will be described with reference to the diagram of Fig. 2.

Three phase current is supplied through the three wires, A, B, C and the transmission of energy to the system is controlled by a three pole switch S, which is closed when the apparatus is in operation.

When the switch S is closed the three wires A, B, C lead to a reversing switch which is of commercial construction and is housed within a metal casing for controlling the motor 11. Each of the wires A, B, C has two branches, leads going from the wire A to the contacts a, a', from the wire B to the contacts b, b', and from the wire C to the contacts c, c', of the two contactors in the reversing switch for controlling the motor 11.

When the coil 35 of the contactor L3, shown at the left in Fig. 2, is energized, a connection is made between the contacts *a*, *b*, *c* and the wires 36, 37 and 38 leading to the motor to drive it in one direction.

When the coil 39 of the contactor R3, shown at the right, is energized, the circuit is completed through the contacts *a'*, *b'*, *c'* with the wires 36, 38 and 37 to drive the motor 11 in the opposite direction. It is to be noted that the order of the wires 36, 37, 38 with respect to contactor R3 is different from their order with respect to the contactor L3 so as to effect a reverse driving of the motor.

To control the contactors R3 and L3, I take a pair of leads 40, 41 from any two of the wires A, B, and C. In the diagrams, I take these leads from the contacts *a'*, *c'*. These two wires 40 and 41 connect to two poles of a manually operated switch S', which is conveniently mounted on the instrument panel of the machine and normally is closed. From the switch S', the wire 40 continues as 42 to one pole of the control switch R, whose operation is controlled by shifting of the band 24, as shown in Fig. 6. In Fig. 2 I have shown this switch R as closed. The wire 42 continues from switch R as 43 to one side of the coil 44 of a relay R1. The wire 43 continues from the other side of the relay coil to one side of the coil 45 of a relay R2 and from there the wire 43 continues to the opposite pole of the switch R. From the switch R the circuit continues past its junction at 46 with an alarm circuit, presently to be described, down to its junction at 47 with one of the relay circuits, thence on as wire 43 to the opposite pole of the switch S1.

It will thus be seen that when the switch R is closed the coil 44 of the relay R1 is energized through the circuit 40, 42, 43, 41 just described.

When the relay R1 is energized it closes the contact 48 which is included in a circuit with the timing switches T1 and T2 which in turn control the circuit of the relay R2 and a system of audible and visible signals 49, 50, 51 and 52 which preferably are located, one pair of each, at opposite ends of the oven so that when the band is off center it will be called to the attention of the operator by either one of the audible signals 49, 50 or one of the visible signals 51, 52.

The timing switch T2 is the long interval switch previously referred to and is automatically set or reclosed at the end of each time interval for which it has been adjusted. Thus, if it be adjusted so as to operate the motor 11 at five minute intervals then at the end of each of these periods it is automatically closed.

The timing switch T1 is the short interval switch and its opening and closing movements are controlled by the motor TM and clutch coil C so that the switch T1 will remain closed for a short interval usually from two to four seconds when the switch T2 is also closed and the relay R1 energized. In Fig. 2, I show both of the switches T1 and T2 closed.

The timing switches T1, T2, timing motor TM, and clutch coil C are shown only diagrammatically, the four constituting a commercial form of control unit that is housed within a metal box or casing indicated by the dash lines D, this being a conventional showing of such a control unit. In a usual construction, the movable element of each timing switch T1, T2, comprises two or more cam discs mounted on a shaft driven by motor TM. The discs of each switch are angularly adjustable with respect to each other and with re-

spect to the shaft, so that the crest or high part of the cam that closes the contact may be long or short, thus holding the switch closed for a longer or shorter interval, and the closing may occur earlier or later during the cycle. Thus if the cycle of switch T2 be set for a five minute interval, the cam discs may be set for a closing period of any length, as say ten seconds, and that closing period may be made to occur at any time during the five minute cycle. The closed period of switch T2 usually is longer and never less than that of T1, and T1 is set to close during the closed interval of T2. The timing switch assembly is not per se a part of my invention, but I have described a commercial form of such apparatus so that its use in my invention will be clearly understood.

Assuming now that the band has shifted slightly to the right of Fig. 6 so as to have closed the control switch R, as shown in Fig. 2, the relay R1 has been energized and the contact 48 closed through the circuit previously described. When the contact 48 is closed, the line up to one side of the timing motor TM is a "live" line comprising wire 43 from switch S', to connection 47 and thence by wire 47' to contact 48, and wire 75 to one side of motor TM. The lead from the other side of motor TM is through wire 57 to switch T2. When T2 is closed, the circuit is completed through wire 58 back to the opposite pole of switch S'. This starts the motor TM which will operate to close switch T1. This completes the circuit through the coil of the relay R2 and also the circuit for the signals 49-52. The circuit to the signals 49-52 will next be described. The wire 43 leading from the source of power is connected at 46 to a wire 53 to which one side of each of the four signals is connected, all in parallel. The opposite side of each of the signals is connected to a wire 54 which extends across and down to one side of the coil 45 of the relay R2 and then to a connection 55 with a wire 56 which leads to one side of the timing switch T1. From T1, a wire 57 leads to the timing switch T2 and thence by wire 58 to one of the poles of the switch S' to which the wire 40 from the main line is connected. This completes the circuit through the signals all of which are operated simultaneously when the relay R1 is closed and the timing switches T1 and T2 are closed.

As previously described, one side of the coil 45 of the relay R2 is connected through the switch R with the wire 43 and the opposite terminal of this coil is connected to the wire 55 which is a part of the circuit for the signals when the timing switches T1 and T2 are closed so that when the signals are operated the relay R2 is also energized. When this occurs the contact 59 is closed, this being in the circuit of the contactor R3 which controls the operation of the motor 11 in one direction. This circuit will be described next. A wire 60 leads from the terminal *a'* through an automatic cut-out or overload relay 61 leading to one side of the coil 39 of the contactor R3. From the opposite side a wire 62 leads to a second overload relay 63 from which a wire 64 leads to one side of the limit switch R4. This limit switch as previously described in connection with Figs. 3 and 4 is normally closed and is open only when the bearing 3 has been shifted up to its allowable limit. From switch R4 the wire 64 leads to one side of the contact 59 of the relay R2; a wire 65 leads from the other side of the contact 59 to a wire 47' which is connected at 47 to the wire 43 which leads through the switch S' to the wire 41

that is connected to the terminal *c'* thus completing the circuit through the coil 39 of contactor R3. This energizes the coil 39, closes the contactor and connects the terminals *a'*, *b'* *c'*, with the wires 36, 38, 37 to drive the motor 11 in one direction. This circuit remains closed and the motor 11 is driven for a short interval until the switch T1 opens which breaks the circuit to the signals and also opens the circuit of the relay R2 which causes the contact 59 to open and break the circuit to the coil 39 of the contactor R3. This causes contactor R3 to open and stop the motor. Now even though the switch R remains closed, the motor will not run again until after the elapse of the interval for which the timing switch T2 is set. The interval of the timing switch T2 usually is determined by the time which it takes the band 24 to travel the length of the oven. When the bearing 3 of the drum 6 is shifted slightly, the effect of this correction cannot be fully determined until the oven band has traveled the length of the oven. Usually a shifting of the bearing 3 for a few thousandths of an inch will be sufficient to correct the alignment of the drums and cause the band to travel back to its central or neutral position. However, if it is not fully corrected by the first "nudging over" of the bearing 3, and the switch R remains closed, then at the end of the proper time interval the switch T2 will again be automatically set and the motor 11 will run for another short interval, to nudge the bearing 3 over a little further. This will continue until the band is returned to central position and the switch R opened. In order to prevent the bearing 3 from being shifted too far by repeated nudges in one direction, I provide the limit switches R4 and L4. The switch R4 operates in conjunction with the relays R1, R2 and contactor R3. The abutment 18 previously referred to is adapted to strike the abutment 20 when the bearing 3 is being shifted too far (by reason of the switch R being closed) and open the limit switch R4 which breaks the circuit to the motor contactor R3 so that the motor 11 cannot be operated but the signals 49-52 continue to operate at intervals as controlled by the timing switch T2.

When the band 24 shifts to the left (Fig. 6) so as to close the control switch L, the relays L1, L2, and contactor L3 are energized so as to complete the circuit to the motor 11 and drive it in the opposite direction and also to operate the signals 49-52 as will now be described.

The wire 42 is connected at 66 to a wire 67 leading to one pole of the switch L. A wire 68 leads from the opposite terminal of the switch to one side of the coil 69 of the relay L1. From the opposite side of this coil a wire 69 leads to one side of the coil 79 of the relay L2 from which a wire 71 leads to the opposite pole of the switch L. The opposite terminal of this switch L is connected to a wire 72 which is connected to the wire 43 which leads back to the switch S' to complete the circuit. This energizes the relay L1 which closes the contacts 73 in a circuit which includes the timing switches T1, T2 and relay L2 and the signals 49-52. When the relay L1 is energized, the contacts 73 are closed which leads current up to one side of the timing switch motor TM so that it is ready to operate to close the timing switch T1 as soon as the timing switch T2 is reset which as previously stated is done automatically at the end of each time interval. The circuit from the relay L1 comprises a wire which is connected at 74 to the wire 47' which in turn

is connected to the live wire 43 from the main line. From the opposite side of the relay contact a wire 75 leads to the timing motor TM and by a wire 57 to one side of the timing switch T2. 5 The opposite side of the timing switch is connected by wire 58 to one terminal of switch S' so that the motor TM will set the switch T1 as soon as T2 is closed.

When the switch T1 is closed this also completes the circuit through the coil of the relay L2. As previously described, a live wire 71 leads to one side of the coil of relay L2 and when switch T1 is closed, the circuit is completed through the wire 56, switches T1, T2 and wire 58 back to switch S' and through that to wire 40 and terminal *a'*.

Energizing relay L2 closes the contact 76 which completes the circuit of the motor control contactor L3. This circuit is as follows: The terminal *c* is connected with the terminal *c'* which is connected by the wires 41 and 43 to the wire 47' which is connected by the wire 77 to one side of the relay contact 76. When this contact is closed, the circuit continues through wire 78 to 25 limit switch L4 and then by wire 79 to a short wire 80 in the motor control contactor box which in turn is connected to an overload cut-out 81 thence by wire 82 to one side of the contactor coil 35. From the opposite side of the coil, a wire 83 leads to a second overload cut-out 84 from which a wire 85 leads to the terminal *a*. This completes the circuit through the contactor coil 35 which is now energized and connects the terminals *a*, *b*, *c*, with the wires 36, 37, 38 to drive 35 the motor 11 in the direction opposite to that which it was driven when the switch R was closed. The motor now runs for a few seconds until the switch T1 is opened after which it remains inactive until the band has traveled the length of 40 the oven and then if sufficient correction has not been made the timing switch T2 will be closed and another short impulse imparted to the motor 11. This continues until sufficient correction has been made and the band returned to its normal 45 position or until the abutment 19 strikes the abutment 21 and opens the limit switch L4.

The circuit for the signals 49-52 is also completed when the timing switch T1 is closed following the closing of control switch L and comprises the same wires and connections as when the control switch R is closed.

While I have shown my invention as embodied in a device for keeping an endless band and a drum running in alignment, it is equally adapted to keeping other parts of the oven or feeding and delivery conveyors running in alignment with the baking band. In some types of ovens, there are two or more bands or conveyors which receive the goods successively, each preceding 55 an apron or band delivering the goods to the next succeeding band. It is necessary that these bands or aprons be kept accurately in alignment. It is within the contemplation of my invention, that the motor 11 may be connected to shift one 60 or the other of two bands, or one of the drums or guides over which they run to restore them to alignment in case one of the bands runs to one side.

It will also be understood that the drawings and terms used are but illustrative of the invention and are not to be construed as limitations thereon. The invention may be embodied in many other forms and can be used with many types of ovens, dryers, belts, conveyors and other apparatus. I claim as my invention all such de-

vices and equivalents thereof that come within the scope of my claims.

What I claim is:

1. In a control device of the character described, the combination with an endless band passing around drums spaced apart of a control switch mounted adjacent each edge of one run of the endless band, each of said switches being normally open and adapted to be closed by contact with the edge of the band adjacent the switch upon lateral movement of the band toward it, means actuated upon closing of either of said switches to shift one of said drums angularly by recurring impulses until said band moves away from said closed switch, means for operating a signal intermittently upon closing of said switch, and means for stopping said impulses when said drum has been shifted angularly a predetermined distance in either direction and the operative control switch remains closed, whereby said shifting means becomes inoperative and said signal continues to operate intermittently.

2. In a control device of the character described, the combination with an endless band passing around drums spaced apart of means for returning the band to central position on the drums when it runs to either side comprising a shaft upon which one of the drums is mounted, a bearing for each end of the shaft, one of said bearings being mounted to slide perpendicular to said shaft, a screw threaded spindle connected to said bearing so that rotation of the spindle will slide the bearing, a reversible electric motor connected to rotate said spindle in either direction, a pair of control switches, electric circuits connecting said switches to said reversible motor whereby upon closing one switch the motor will be driven in one direction and upon closing the other switch the motor will be driven in the opposite direction, means actuated by the band for closing one of said control switches when the band runs to one side on the drums, means actuated by the band for closing the other control switch when the band runs to the other side on the drums, timing switches controlling said circuits whereby said circuits will be interrupted at spaced time intervals when either of said control switches is closed, and means actuated to open the operative motor circuit when said bearing has been shifted a pre-determined amount and the control switch in the operative motor circuit remains closed.

3. In a control device of the character described, in combination an endless band passing around drums spaced apart, a shiftable bearing for one of said drums, a reversible motor, a pair of circuits for said motor, connections between said motor and shiftable bearing whereby said motor may shift the bearing in either direction, a contactor in each of said motor circuits that is normally open, a motor control circuit for each of said contactors, a relay operated contact in each of said motor control circuits, two control switches that are normally open, each control switch associated with one edge of said band, devices associated with each switch whereby one switch will be closed upon side shifting of the band on the drums, a timing switch connected in circuits with the relays operating the motor control circuit contacts, relay controlled contacts in said timing switch circuits, and circuits including relays operating said timing switch contacts on said control switches, whereby upon closing of either of said control switches by shifting of the band

5 the corresponding timing switch circuit will next be closed which will energize the relay operating the motor control contact in the associated motor control circuit and close a motor circuit to drive the motor in one direction to shift the drum bearing and return the band to central position.

4. In a control device of the character described, in combination an endless band passing around drums spaced apart, a shiftable bearing for one of said drums, a reversible motor, a pair of circuits for said motor, connections between said motor and shiftable bearing whereby said motor may shift the bearing in either direction, a contactor in each of said motor circuits that is normally open, a motor control circuit for each of said contactors, a relay in each of said motor control circuits, two control switches that are normally open, each control switch associated with one edge of said band, devices associated with each switch whereby one switch will be closed upon side shifting of the band on the drums, a timing switch connected in circuits with said motor circuit relays, relay controlled switches in said timing switch circuits, circuits including said timing switch relays and control switches, whereby upon closing of either of said control switches by shifting of the band the corresponding timing switch circuit will next be closed which will energize the relay in the associated motor control circuit and close a motor circuit to drive the motor in one direction to shift the drum bearing and return the band to central position, an electrically operated signal, a circuit for said signal including said timing switch whereupon said signal will be operated when said timing switch is closed.

5. In a control device of the character described, in combination an endless band passing around drums spaced apart, a shiftable bearing for one of said drums, a reversible motor, a pair of circuits for said motor, connections between said motor and shiftable bearing whereby said motor may shift the bearing in either direction, a contactor in each of said motor circuits that is normally open, a motor control circuit for each of said contactors, a relay in each of said motor control circuits, two control switches that are normally open, each control switch associated with one edge of said band, devices associated with each switch whereby one switch will be closed upon side shifting of the band on the drums, a timing switch connected in circuits with said motor circuit relays, relay controlled switches in said timing switch circuits, circuits including said timing switch relays and control switches, whereby upon closing of either of said control switches by shifting of the band the corresponding timing switch circuit will next be closed which will energize the relay in the associated motor control circuit and close a motor circuit to drive the motor in one direction to shift the drum bearing and return the band to central position, a limit switch that is normally closed in each of said motor control circuits, and means actuated by the means which moves said shiftable bearing to open the limit switch in the closed motor control circuit when the bearing has been shifted a predetermined maximum distance.

6. In a control device for an endless band having upper and lower runs passing around drums spaced apart the combination with the endless band of a rotating drum about which the band passes, a shaft upon which the drum is mounted, a bearing for each end of the shaft, means for mounting one of said bearings so that it is slid-

able perpendicular to the shaft and in the direction of the length of the band, shifting means operated by lateral displacement of the band in either direction on said drum to shift said slideable bearing by a slight increment in a direction to cause the band to return to central position, means for interrupting operation of said shifting means until the band has traveled over the drum sufficiently to determine the corrective effect of the shifting of the bearing, said interrupting means operating at recurrent intervals while the band remains displaced to restore operation of the shifting means until the cumulative effect of the recurrent shiftings of the bearing restores the band to central position, and means actuated by the shifting of the bearing for rendering said shifting means inoperative when said bearing has been shifted to a predetermined limit and the band has not been returned to central position.

7. In a control device of the character described, the combination with a driven band having upper and lower runs passing around a rotatable drum of means for returning the band to central position on the drum when it runs to either side comprising a bearing supporting one end of the drum and mounted to slide perpendicular to the axis of the drum and parallel to the run of the band, a reversible electric motor connected to slide said bearing in either direction, two driving circuits for said motor each having a normally open switch, said driving circuits being arranged to drive the motor in opposite directions upon closing of the respective open switches; two control circuits including a common timing switch, two control switches and two limit switches; the limit switches being normally closed and one in each circuit, said control switches being one in each control circuit and positioned one adjacent each edge of the band so as to be closed by pressure of the band upon its shifting to either side, the normally open switches in the motor circuits being controlled by the respective control circuits so that when either of the control switches is closed the normally open motor circuit switch in the associated motor circuit will be closed and opened at each closing and opening of the timing switch, and means connecting the slideable bearing and the normally closed limit switches whereby the closed switch in the operative motor circuit will be opened when the bearing has been shifted a pre-determined distance to open the limit switch and the control switch in the operative control circuit remains closed.

8. In a control device of the character described, the combination with a driven band having upper and lower runs passing around a rotatable drum of means for returning the band to central position on the drum when it runs to

either side comprising a bearing supporting one end of the drum and mounted to slide perpendicular to the axis of the drum and parallel to the run of the band, a reversible electric motor connected to slide said bearing in either direction, two driving circuits for said motor each having a normally open switch, said driving circuits being arranged to drive the motor in opposite directions upon closing of the respective open switches; two control circuits including a common timing switch, two control switches and two limit switches; the limit switches being normally closed and one in each circuit, said control switches being one in each control circuit and positioned one adjacent each edge of the band so as to be closed by pressure of the band upon its shifting to either side, a signal circuit included in each of said control circuits, each signal circuit including said timing switch and one of said control switches, the normally open switches in the motor circuits being controlled by the respective control circuits so that when either of the control switches is closed the normally open motor circuit switch in the associated motor circuit will be closed and opened at each closing and opening of the timing switch, and means connecting the slideable bearing and the normally closed limit switches whereby the closed switch in the operative motor circuit will be opened when the bearing has been shifted a pre-determined distance to open the limit switch and the control switch in the operative control circuit remains closed, so that the associated signal circuit will continue to be closed at each closing of the timing switch.

9. In a control device of the character described, the combination with a driven band having upper and lower runs passing around a rotatable drum of means for returning the band to central position on the drum when it runs to one side comprising a bearing supporting one end of the drum and mounted to slide perpendicular to the drum, a reversible electric motor connected to slide said bearing in either direction, a signal, motor control circuits for driving said motor, signal control circuits for operating said signal, said motor control circuits and signal circuits having a common timing switch opening and closing intermittently and common control switches, each of said control switches being adapted to be closed by shifting of the band to one side on the drum, limit switches in said motor control circuits, means for opening the limit switch in a closed motor circuit when the bearing has been shifted a pre-determined distance and the control switch is still held closed, whereby the motor will be stopped and the signal will continue to operate intermittently.

HARVEY O. MERCIER.
